DESIGN FOR A BOTTLE

Thomas D'Addario, Long Island City, N. Y., assignor to N. H. Darsky, Joe Darsky, Julius Darsky, and Carl Lockshin, Youngstown, Ohio

Application April 6, 1939, Serial No. 84,092

Term of patent 14 years

To all whom it may concern:

Be it known that I, Thomas D'Addario, a citizen of the United States, residing at 25-70 34th Street, city of Long Island City, in the county of Queens and State of New York, have invented a new, original, and ornamental Design for Bottles, of which the following is a specification, reference being had to the accompanying drawing, forming part thereof.

Figure 1 is a side view in elevation of a bottle, showing my new design. Figure 2 is a cross-section on line 2--2 of Figure 1.

I claim:

The ornamental design for a bottle, as shown.

THOMAS D'ADDARIO.
